UNITED STATES PATENT OFFICE.

HENRY TRUST, OF PARK RIDGE, NEW JERSEY, AND FRANK M. ASHLEY, OF BROOKLYN, NEW YORK; SAID ASHLEY ASSIGNOR OF ALL HIS RIGHT TO JOSEPHINE TRUST, OF PARK RIDGE, NEW JERSEY; JOSEPHINE TRUST, ADMINISTRATRIX OF SAID HENRY TRUST, DECEASED.

MIXING AND BEATING MACHINE.

Application filed December 16, 1919. Serial No. 345,344.

To all whom it may concern:

Be it known that we, HENRY TRUST, a citizen of the United States, and resident of Park Ridge, in the county of Passaic and State of New Jersey, and FRANK M. ASHLEY, a citizen of the United States, and resident of Brooklyn, in the county of Kings and State of New York, have invented certain new and useful Improvements in Mixing and Beating Machines, of which the following is a specification.

Our invention relates to mixing and beating machines and the object of our invention is to provide a beater made of wire and a shank portion having a head to hold the ends of the wires of the beater in such manner as to be easily connected to the wires or disconnected therefrom so that wires of different form may be used, depending upon the work to be done and also to make renewals in case a wire is bent or broken.

A further object is to provide a wire construction in which the wire of one unit will extend across the open space between the wire of the adjacent unit in order to more quickly and effectively provide the finished product.

Referring to the drawings which form a part of this specification:

Figure 1 is a plan view of a construction embodying our invention, the cap of the wire holder being shown in cross section.

Figure 2 is a vertical view, partly in section.

Figure 3 is a vertical sectional view through the cap portion of the wire holder.

Figure 4 is a perspective view of the body portion of the wire holder.

Figure 5 is a plan view of the construction illustrated in Figure 4.

A indicates the body portion of the wire holder which consists of a metal casting having a threaded periphery A' and a conical top portion B and provided with slots C—C—C, etc., the depth of which is less in the conical portion B than the diameter of the wire to be held and the lower portion of which is at an even distance from the surface below the threads so that the ends of the wires will be bent inward at an angle to the vertical as illustrated in Figure 1 in the conical portion and rest below the threads in the vertical portion of the slots,

so that the co-acting thread D' in the cap portion D will not be stripped or injured when it is screwed onto the body portion. When the cap portion D is screwed onto the body portion A, the conical surface D² contacts with the ends of the wires at their sides and holds them firmly in place, the conical surfaces B' and D² coming in contact and frictionally engaging to hold the parts together. E indicates the shank which is shown as formed integral with the body portion A but if preferred it may be made as a separate part and connected to the body portion by a screw thread joint or in any other suitable manner.

The dotted lines F indicate a receptacle, and the path of the outer ends of the wire loops G—G—G, etc., are arranged to come close to the inner sides of the receptacle in their travel.

In the present construction we show four elements of wire, each being a duplicate of the other in their general form but specifically different in that some have loops at the bottom of less width than others to permit the wires of one element to come in a horizontal plane with the middle of the space of the adjacent element as for illustration, wire H will cross the middle of the space I of wire J in its travel. Each wire unit, for illustration, shows that one having the loops G is bent in such manner that its inner loops G'—G', etc., extend across the vertical centre of the shank E and each is formed with a vertical member G²—G², etc., respectively, which serves to brace the loops G—G—G, etc., and to sweep the inner sides of the receptacle F. It will be further observed that certain loops, as for illustration K, abut the adjacent wire at K' and again at K² and K³, so that a bracing construction is formed that helps to stiffen the beater. It is believed that the drawings will better illustrate the construction than a written description and therefore further description is deemed unnecessary.

Having thus described our invention, we claim as new and desire to secure by Letters Patent:

1. A beater comprising a body portion having a thread formed in its surface and slots intersecting said threads, a cap adapt-

ed to overlie said slots and having threads to engage the threads in the body portion.

2. A beater comprising a body portion having a thread formed in its surface and slots intersecting said threads, a cap adapted to overlie said slots and having threads to engage the threads in the body portion, and beater units formed of wire, the ends of which are placed in said slots and held 10 in position by said cap.

3. A beater comprising a body portion having a thread formed in its surface and slots intersecting said threads, a cap adapted to overlie said slots and having threads 15 to engage the threads in the body portion and a plurality of units made of wire suspended from said head, each of which is

formed with loops which overlap the loops in the adjacent unit.

4. A beater comprising a body portion 20 having a thread formed in its surface and slots intersecting said threads, a cap adapted to overlie said slots and having threads to engage the threads in the body portion and a plurality of units made of wire suspended 25 from said head, each of which is formed with loops which overlap the loops in the adjacent unit and a shank formed integral with said body portion.

Signed at New York city, in the county of 30 New York and State of New York, this 13th day of December, A. D. 1919.

HENRY TRUST.

FRANK M. ASHLEY.
